BAIL FOR DOOR KNOCKER

LaVerne E. Clayton, Rockford, Ill., assignor to
Amerock Corporation, Rockford, Ill.

Filed May 25, 1970, Ser. No. 33,115

Term of patent 14 years

Int. Cl. D8—09

U.S. Cl. D8—177

FIG. 1 is a front view of a bail for door knocker incorporating my new design.

FIG. 2 is a side view of the bail for door knocker as seen from the right in FIG. 1.

FIG. 3 is a top view of the bail for door knocker.

FIG. 4 is a bottom view of the bail for door knocker.

FIG. 5 is a sectional view taken along the line 5—5 in FIG. 1.

FIG. 6 is a sectional view taken along the line 6—6 in FIG. 1.

FIG. 7 is a sectional view taken along the line 7—7 in FIG. 1.

FIG. 8 is a sectional view taken along the line 8—8 in FIG. 1.

FIG. 9 is a sectional view taken along the line 9—9 in FIG. 1.

FIG. 10 is a sectional view taken along the line 10—10 in FIG. 1.

I claim:

The ornamental design for a bail for door knocker, as shown.
